UNITED STATES PATENT OFFICE.

EMILY G. HUMPHREY, OF SAN FRANCISCO, CALIFORNIA.

NAPKIN SUPPORT.

Application filed May 2, 1927. Serial No. 188,261.

The present invention relates to an improved napkin support particularly adapted for children's use, wherein it is desired to suspend a bib or napkin in a spread position over the bosom of the wearer.

The objects of the invention are to provide a support for detachably mounting a napkin or bib, which, when in position on the wearer, will suspend the napkin or bib in a spread position across the bosom of the wearer without the use of clips, clamps, or other movable parts, and one which may be inexpensively manufactured, pleasing in appearance, and adapted to ornamentation and inscription.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To comprehend the invention, reference is directed to the accompanying drawings, wherein:—

Figure 1 is a view in front elevation of the preferred embodiment of my invention.

Figure 2 is a view in front elevation of the disclosure in Figure 1 with a napkin supported therein.

Figure 3 is a sectional view taken on line 3—3 of Figure 2.

Figure 4 is an end view of my invention illustrating one end of a cord or chain secured thereto.

In the drawings wherein like characters of reference designate corresponding parts in the several views, 1 indicates a plate illustrated as arcuate in elevation. The face of the plate 1 is provided with a plurality of parallel longitudinally disposed arcuate slots 2 and 3 separated by a plate body portion 3', the upper slot 2 being of a length slightly less than that of the lower slot 3.

In the embodiment illustrated the edges of the slots 2 and 3 extend parallel with the top and bottom edges of the plate 1. The end walls of the plate are each inwardly and downwardly slotted at 5 forming upwardly extending hooks 6 one at each end of the plate. One end of the plate is slotted

inwardly and upwardly at 7 communicating with one of the slots 5 forming a downwardly extending hook 8 over which is adapted to be slipped the looped end 9' of a plate retaining chain or cord 10, the other end 11 of which is passed through the aperture 12 in the opposite end of the plate as shown in Figure 1. The knotted portion 9 of the free end of the member 10 may be secured in slot 7 as illustrated if desired. The napkin 4 is detachably secured to the plate by passing one corner thereof from the rear of the plate outwardly through the slot 3 over the body portion 3' and inwardly through the upper slot 2, then downwardly to lie adjacent the rear face of the main portion of the napkin. That portion of the napkin passed through the plate slots is shirred so as to cause a spreading of the depending portion of the same, as shown in Fig. 2. If desired, the end portion of the napkin, after being passed through the slot 2, may be positioned over the upper peripheral edge of the plate and downwardly lying parallel with the main portion of the napkin, as shown in the dotted lines in Figure 3. To widen the spread of the napkin, the edges thereof may be passed through the end slots 5, the hooks 6 holding the same in position within said slots. When the cord or chain 10 is passed around the neck of the wearer and the free end 9' is fastened to the hook 8, or the knot 9 is received in slot 7, the napkin is suspended so as to cover the body portion of the wearer.

It will be apparent that the plate may be of any desired shape just so the slots therein are of arcuate formation with the lower slot of slightly greater length to insure a spread of the napkin or bib supported. It will also be understood that it is not necessary to remove the napkin from the support each time the support is removed from the wearer, as the support may be provided with ornamentation or inscription identifying the wearer.

I claim:—

1. A bib or napkin holder comprising an elongated body formed longitudinally with a pair of parallel spaced arcuate slots arranged side by side, said slots affording a means for threading a napkin edge through the holder body with the body of the napkin depending from the holder body with its side edges diverging, and means carried by the holder body for positioning around

the neck of the wearer to suspend the holder body transversely across the bosom of the wearer with the arc of the slots downwardly disposed.

- 5 2. A bib or napkin holder comprising an elongated body formed longitudinally with an elongated slot affording a means for threading a napkin edge through the holder body and around the solid portion thereof,
- 10 with the body of the napkin depending from the holder body, a flexible means connected at one end with one end of the holder body, the opposite end of the holder body provided with a slot for receiving the free end of the
- 15 flexible means, whereby the flexible means is adapted for positioning around the neck of the wearer, with its free end received in said slot to suspend the holder body transversely across the bosom of the wearer.
- 20 3. A bib or napkin holder comprising an elongated segmentally shaped body formed

longitudinally with a pair of parallel spaced arcuate slots arranged side by side with their side edges disposed parallel with the side edges of the body, said slots affording 25 a means for threading a napkin edge through the holder body, said body provided at its ends with inwardly extended slots for receiving the side edges of the napkin, a flexible member connected at one end to one 30 end of the holder body, said holder body at its opposite end being inwardly slotted for receiving the free end of the flexible means, whereby said means when positioned around the neck of the wearer is adapted to suspend 35 the holder body transversely across the bosom of the wearer with the arc of the slots downwardly disposed.

In testimony whereof I have signed my name to this specification.

EMILY G. HUMPHREY.
